UNITED STATES PATENT OFFICE.

OTIS M. CUTLER, OF WAKEFIELD, MASSACHUSETTS, ASSIGNOR TO
FIBERED LEATHER MANUFACTURING COMPANY, A CORPORA-
TION OF MAINE.

LEATHER-SHREDDER.

No. 819,862.

Specification of Letters Patent.

Patented May 8, 1906.

Application filed January 28, 1902. Renewed March 22, 1904. Serial No. 199,429.

To all whom it may concern:

Be it known that I, OTIS M. CUTLER, a citizen of the United States, residing at Wakefield, in the county of Middlesex and State of Massachusetts, have invented certain new and useful Improvements in Leather-Shredders; and I do hereby declare the following to be a full, clear, and exact description of the invention, such as will enable others skilled in the art to which it appertains to make and use the same.

This invention relates to processes of shredding leather and to apparatus therefor; and it consists in the novel process for shredding scrap and other leather as well as in the novel construction and combination of parts hereinafter fully described and claimed.

In the drawings, Figure 1 is a side view of the machine. Fig. 2 is a front end view. Fig. 3 is a longitudinal section through the shredding mechanism, drawn to a larger scale. Fig. 4 is a detail side view, and Fig. 5 is an end view, of the shredding-cylinder. Figs. 6 and 7 are respectively a side view and an end view of the fingers. Fig. 8 is a longitudinal section through the shredding-cylinder.

A is the frame of the machine, provided with a table B at its upper part for the scrap-leather to rest on. Two openings b and b' are formed in the table B.

C is a conveyer which works in the opening b and has its upper surface arranged flush with the top of the table. This conveyer consists of a broad endless belt which passes over two rollers c and c', which are journaled in the frame A. The front roller c is the driving-roller, and it is revolved by any approved driving devices.

D is a smooth feed-roll, which is journaled in the frame A over the roller c' and revolved in the direction of the arrow in Fig. 3 by any approved driving mechanism.

E and E' are two corrugated feed and consolidating rollers which are journaled in the frame A behind the rollers D and c', and which are revolved by any approved driving mechanism. The lower roller E' projects upwardly in the opening b' of the table, so that its periphery is substantially in the plane of the top of the table.

F is a shredding-cylinder consisting of a series of saws mounted on a driving-shaft f

and held apart by distance-pieces or washers f'. The shaft f is journaled in bearings g, carried by a saddle G, which is slideable cross-wise of the table in guides g'. The shredding-cylinder and the upper feed-rollers are provided with suitable casings H and h, the casing H being secured to the saddle G and the casing h to the frame A.

I represents fingers arranged in a series and secured to the saddle G. These fingers project between the saws on the lower side of the shaft, and they have notches i at their free ends. The bottoms of the notches are level with the table-top, and they and the upwardly-projecting portions of the fingers prevent the scraps of leather from being forced between the saws without being shredded by the saw-teeth.

J is a hopper or chute for the shredded leather arranged under the shredding-cylinder. The shredding-cylinder is reciprocated crosswise of the machine by means of a cam K and a lever k. The lever k is pivoted on a pin k', supported by a cross-bar a' of the frame A, and its upper end is pivoted to the saddle G by a pin m. The lower end of the lever has a shoe m', which engages with the cam. The cam K is secured on a shaft N, which is journaled in the frame A.

P is the driving-shaft of the machine, which is revolved by a belt-pulley P' or in any other approved manner. A toothed wheel p is secured on the driving-shaft P and gears into a toothed pinion p' on the shaft of the lower feed-roll E'. The pinion p' also gears into a toothed pinion q on the shaft of the upper feed-roller E. The upper feed-roll D also has a toothed pinion q secured on it, and q' is an idle toothed wheel which gears into the two pinions q, so that the upper feed-rollers revolve simultaneously and in the same direction. The toothed wheel p also gears into a toothed pinion s, secured on the cam-shaft N. The shredding-cylinder is revolved by means of a belt-pulley t, secured on its shaft, a belt-pulley s', secured on the shaft N, and a belt t', which passes over the pulleys s' and t.

The conveyer-roller c is revolved by means of a belt-pulley v, secured on its shaft, a belt-pulley w, secured on the cam-shaft N, and a belt w', which passes over the pulleys v and w. Other equivalent driving mechanism may,

however, be used for imparting motion to the various parts of the machine in carrying out this invention.

The scraps of leather are placed on the conveyor, which forms a portion of the feed-table. This conveyor and the smooth feed-roll feed the scraps of leather over the surface of the table into engagement with the corrugated feed-rollers. The scraps are consolidated by the corrugated feed-rollers and are pressed by them against the saws of the shredding-cylinder in the notches of the fingers. The consolidation of the scraps by the corrugated feed-rollers into a sort of cake enables the scraps to be presented to the saws so that every portion of them is shredded up as the shredding-cylinder is reciprocated back and forth and revolved. The shredded leather falls into the hopper or chute and is carried away in suitable receptacles placed under the chute to receive it.

The shredded leather is used in the arts for various purposes, but chiefly for making sole and heel plates for shoes, being mixed with other suitable ingredients and formed into slabs or sheets by a suitable process. It may be employed wherever a fabric or composition is desired having the toughness and wear-resisting and other qualities of leather. The only processes heretofore proposed for shredding leather of which I am aware are the so-called "wet" processes, in which the leather is subjected to soaking in order to partially disintegrate it and is then tumbled or beaten to separate its fibers. This leaves a wet product from which it is very difficult to exclude moisture and a product which is unsuitable for many of the purposes for which my invention may be employed.

40. What I claim is—

1. In a shredding-machine, the combination, with a shredding-cylinder, of a flat table arranged in front of the cylinder and provided with two openings, an endless conveyor belt provided with end rollers and having its upper portion working in one of the said openings, a pair of feed and consolidating rollers arranged between the said conveyor and shredding-cylinder, the lower roller of the said pair being arranged in the other said opening of the table, a feed-roll arranged over the rear end roller of the said conveyor, and driving mechanism for the said conveyor, rollers, roll and cylinder, substantially as set forth.

2. In a shredding-machine, the combination, with feeding mechanism for the material, of a revoluble shredding-cylinder, and driving devices operating to reciprocate the said cylinder

60. der crosswise of the direction of the feed of the material, substantially as set forth.

3. In a shredding-machine, the combination, with a table, and feed mechanism for moving the material longitudinally of the table; of a revoluble shredding-cylinder, and driving devices operating to reciprocate the said cylinder crosswise of the table, substantially as set forth.

4. In a shredding-machine, the combination, with feeding mechanism for the material, of a frame supporting the said feeding mechanism and provided with guides arranged crosswise of the direction of the feed of the material, a saddle slidable in the said guides, a shredding-cylinder journaled in the said saddle, a pivoted lever for reciprocating the said saddle, and a revoluble cam for operating the said lever, substantially as set forth.

5. In a shredding-machine, the combination, with feeding mechanism for the material, of a revoluble shredding-cylinder comprising a series of saws secured at short distances apart, a series of fingers arranged between the said saws, and driving devices operating to reciprocate the said cylinder and saws crosswise of the direction of the feed of the material, substantially as set forth.

6. In a shredding-machine, the combination, with a table, and feed mechanism for moving the material over the table; of a revoluble shredding-cylinder comprising a series of saws secured at short distances apart, and a series of fingers arranged between the said saws with their free ends adjacent to the edge of the said table and operating to hold the unshredded material in engagement with the saw-teeth, substantially as set forth.

7. In a shredding-machine, the combination, with a table, and feed mechanism for moving the material over the table; of a saddle slidable crosswise of the table, driving mechanism for reciprocating the saddle, a revoluble shredding-cylinder journaled in the saddle and comprising a series of saws secured at short distances apart, and a series of fingers secured to the said saddle and projecting between the said saws with their free ends adjacent to the edge of the said table and operating to hold the unshredded material in engagement with the saw-teeth, substantially as set forth.

In testimony whereof I affix my signature in presence of two witnesses.

OTIS M. CUTLER.
